UNITED STATES PATENT OFFICE.

EDWARD H. MOYLE, OF LOS ANGELES, CALIFORNIA.

DESIGN FOR A CONCENTRATOR-FRAME.

45,431.

Specification for Design.

Patented Mar. 17, 1914.

Application filed January 19, 1914. Serial No. 813,118. Term of patent 14 years.

To all whom it may concern:

Be it known that I, EDWARD H. MOYLE, a citizen of the United States, residing at Los Angeles, in the county of Los Angeles and State of California, have invented a new, original, and ornamental Design for a Concentrator-Frame, of which the following is a specification, reference being had to the accompanying drawing, forming part thereof.

The figure is a perspective view showing my new design.

I claim:

The ornamental design for a concentrator frame, as shown.

EDWARD H. MOYLE.

Witnesses:
